NECKTIE

Hyman W. Lewine, New Rochelle, N. Y., assignor to Wembley, Inc., New Orleans, La., a corporation of Louisiana

Application August 22, 1955, Serial No. 37,605

Term of patent 14 years

(Cl. D3—16)

Fig. 1 is a front elevational view of a necktie as it appears folded over in half;

Fig. 2 is a rear elevational view thereof; and

Fig. 3 is a front elevational view thereof as it appears in tied or wearing position.

The characteristic feature of my design resides in the upper panel on the necktie disclosed, of the taper from the wide portion b to the narrow portions a and c at the upper and lower ends thereof, all as shown.

I claim:

The ornamental design for a necktie, as shown and described.
